UNITED STATES PATENT OFFICE.

SWAN NILS TEVANDER, OF MAYWOOD, ILLINOIS.

SHIPPING TAG.

Application filed August 15, 1923 Serial No. 657,466.

The object of my invention is to make a tag that is not only cheaply made but that will be substantially indestructible and provide an aperture for the easy and quick insertion of the cord or wire through the tag for fastening the same to the article to which it is to be attached.

Large losses are occasioned in shipping by reason of accidental tearing off of shipping tags from the goods, the tags generally being made of paper of some sort. Such paper tags are also subject to virtual destruction from the accidental obscuring of the writing or printing thereon due to crumpling or by moisture, oil, grease or other substances causing dirt to adhere to and become ground into the paper, or by causing writing ink to "run." It is to overcome these losses that I have provided my tag in the form shown.

Reference will be had to the accompanying drawing in which Fig. 1 is a view of the ordinary tag in common use today. Fig. 2 is a transverse section on line 2—2 of Fig. 1. Fig. 3 is a perspective view of my tag. Fig. 4 is a section thru the eyelet hole of my tag as generally made. Fig. 5 shows an alternate construction on the same section as Fig. 4. Fig. 6 is another alternate construction on the same section as Fig. 4. These Figs. 4, 5, and 6 being on a very much enlarged scale. Fig. 7 is a plan view of the tag having the entire margin of the tag turned or hemmed over to escape a raw edge.

In the drawing 1 indicates the ordinary tag which is made of paper or paste board as generally constructed. 2, indicates the eyelet hole thru which the fastening cord or wire is passed. 3 indicates reinforcing washers or wafers pasted on the body 1 of the tag to reinforce the eyelet hole 2. This is ordinary common construction of the tags in general use. In making these tags, reinforcing washers or wafers 3 are made of separate pieces and secured by adhesive material to the body 1 of the tag.

I prefer to make my tag out of thin sheet metal and face this metal with a sheet of paper and in the drawing, 4 indicates the metal sheet and 5 the paper facing. The eyelet hole is indicated by 6 and is produced by making a relatively much larger hole than the old style eyelet hole 2 and turning over the metal of the body of the backing plate 4 in the area of the hole to form an eyelet appearance as indicated by 7. Thus I form out of the metal sheet out of which the tag is

made a large eyelet hole in common practice large enough for one to stick his finger thru so that the cord or wire may be very quickly and easily inserted in this hole, and this is accomplished without the use of any additional material whatever and with substantially no expense. Were a large eyelet hole to be made on the old style tags it would seriously weaken the end of the body sheet 65 of the tag itself, and at the same time would cause the use of much greater material in the reinforcing washers or wafers 3 as they would have to be much larger and the increase in the size of the wafers 3 as to the area of material used is as the square of the diameter so that a small increase in the size of the diameter of the old style wafer or reinforcement 3 is a large increase in the expense of making them, whereas with my 75 metal back paper faced tag there is no increase in cost whatever as related to the normal use of the size of the eyelet hole 6 which permits this hole to be as large as desired for convenience in threading through the tying 80 cord or wire.

The paper surface 5 is secured to the thin metal back 4 by an adhesive material that secures the paper to the metal in a manner to resist moisture, oil and grease so that the 85 paper will not be loosened from the metal by any service that is normally possible for a tag to encounter. The paper facing permits the printing and addressing of the tag with even greater facility than with the old 90 style tags since the metal backing holds a good stiff surface upon which to print or write.

Further the manufacture of the tag itself may be done by automatic machinery with 95 much greater facility than is possible to manufacture the reinforcing wafers 3 as before described.

In Fig. 4, the metal 4 is turned over into the eyelet 7 embracing as it were the paper facing around the eyelet hole 6. In Fig. 5 I may simply turn over a flange 8 without having the beading effect as indicated in Fig. 4.

When desired I double face the metal body 4 with paper on both sides, the under side 105 being indicated by 9 in Fig. 6, and the metal portion will then be sandwiched in between two paper layers.

For some uses the raw edge of the metal on the margin of the tag may be objectionable and in such cases I turn over the edge of the tag in the form of a hem as indicated 110

by 10 in Fig. 7 and this provides a rounded edge and at the same time stiffens the body of the tag. By turning this edge so as to clamp the paper facing aids in holding the facing to the metal body.

5 The application on the paper facing to the metal backing is done in flat sheets or continuous rolls depending on the source of supply of metal which permits the manufacture 10 of the metal paper coated sheet at very little expense and then these prepared sheets are delivered to the automatic machine which 15 cuts out the tags and forms the eyelet holes without having to handle any separate pieces of adhesive material which is a great desideratum.

The metal body of my tag may be very thin for the average service required of a tag. Likewise the paper may be of rather cheap 20 quality and relatively thin. The adhesive material necessary to hold this thin paper on to the metal is also a very thin coating and as it requires very simple machinery to apply this thin paper to the metal body, the 25 cost of these tags is low.

I use an adhesive that is not subject to the action of water, oil and grease and hence I may use a cheaper quality of paper, a quality 30 which is really cheaper than what would be serviceable for writing an address upon, owing to the fact that this paper is supported

by the metallic back or body of the tag. With ordinary shipping tags a strong high priced quality of paper is necessarily used.

By making a large eyelet hole as I do I 35 am able to use the metal that occupied the space near the margin of this hole to reinforce the margin around the hole, and this is not practicable with a small eyelet hole because this would involve an excessive 40 stretching of the metal at its center. A large hole is desirable, and because I reinforce the margin of this eyelet hole by the metal of the back there is no tendency to cut the cord because of the thinness of the metal 45 body of the tag. Thus my construction arrives at the most desirable form of tag with which I am in any manner familiar.

What I claim is:—

A laminated tag comprising a layer of 50 metal and a layer of softer sheet material such as paper coextensive with the metal and adherent thereto with the marginal area doubled over into a bead or hem with the metal extending around and forming the extreme outer layer of the bead or hem embracing the softer material to protect it against rupture or separation from the metal.

Signed at Chicago, in the county of Cook and State of Illinois, July, 1923.

SWAN NILS TEVANDER.
